GEORGE W. BOWEN, OF AUBURN, NEW YORK.

PROCESS OF MAKING LUBRICATING DEVICES OR GREASE-CUPS.

1,098,873.

Specification of Letters Patent.

Patented June 9, 1914.

Application filed July 11, 1913. Serial No. 778,548.

To all whom it may concern:

Be it known that I, GEORGE W. BOWEN, a citizen of the United States, and a resident of Auburn, in the county of Cayuga and State of New York, have invented a certain new and useful Process of Making Lubricating Devices or Grease-Cups, of which the following is a specification.

This invention has for its object a process for producing a lubricating device or grease cup and particularly a method of attaching a sheet metal cup or head to the stem of the device; and the invention consists in the steps hereinafter set forth and claimed.

In describing this invention reference is had to the accompanying drawings in which like characters designate corresponding parts in all the views.

Figures 1, 2, 3 and 4 are vertical sectional views of the tools and parts being operated on, Fig. 1 illustrating the drawing and reducing operation by which a cup shape shell is formed having a reduced hexagonal base portion, Fig. 2 illustrating the operation of punching a hole in the bottom of the shell formed by the operation illustrated in Fig. 1, and Figs. 3 and 4 illustrating successive reducing operations by which the barrel portion of the shell above the base is compressed into a circle of less diameter than the base of the shell in order to clamp the shell on the flange of the stem.

This process consists in taking a cup shape shell closed at one end, punching a central hole in the closed end of the shell, passing a hollow stem which has a flange at one end through the opening until the flange rests upon the bottom or wall around the opening, and compressing the barrel portion of the shell above that in which the flange is located, into a circle of less diameter than the portion containing the flange. Usually, the process also consists in reducing the base portion of the shell, that is, the portion adjoining the closed end and thickening the walls of the same and forming said base hexagonal by drawing and pushing the shell into a reducing die by a tool bearing on the inner face of the bottom or closed end of the shell and also on the edge of the shell, the inner end portions of the tools or dies being hexagonal and the remaining portions cylindrical.

In Fig. 1, 1 designates the shell which is formed in a well known manner by successive drawing operations from a flat blank,

2 and 3 are respectively male and female die members, the member 2 having its lower end 4 formed hexagonal for fitting into the reduced hexagonal portion 5 of the die 3. In the operation shown in Fig. 1, the shell 1, which is substantially the length of the finished cup, is placed in a female die member 3 and the male die member or tool 2 is moved into the shell 1, the hexagonal portion 4 bearing against the inner face of the bottom or closed end 6 of the shell and drawing the same into the portion 5 of the die 3, and a shoulder 7 on the tool or die member 2 engaging the upper edge of the shell 1 and pushing the shell into the die member 3 and maintaining the length of the shell and thickening the wall of the base or hexagonal portion 8 of the shell. The thickening of the base 8 is brought about by the pushing operation and by forming the die members 2 and 3 so that there is a greater space between the hexagonal portions 4 and 5 thereof than between their cylindrical portions.

The shell 9 formed by the operation shown in Fig. 1 is placed in a suitable die 10 and the hole 11 is punched therein by a tool 12. The hole punching operation may be effected in any well known manner. The perforated shell 13 is then placed in a die 14, Fig. 3 which has a cavity fitting the base 8 of the shell 13, the barrel portion of the shell above the base 8 projecting out of the cavity. The stem 15 having an hexagonal flange 16 at its upper end of sufficient size and shape to fit within the hexagonal base, is passed through the opening 11 until said flange 16 fits within the base 8. A reducing die 17 is then passed over or around the portion 18 of the shell 13 above the base 8 reducing the barrel portion 18 of the shell into a circle of less diameter than the base 8 and thereby forming the shell 19. The die 17 moves lengthwise of the shell from the open end thereof toward the closed end, and the shell is held from elongating by the tool 20 bearing against the edge of the open end of the shell after the reducing operation has been started. As the die 17 moves toward the die 14, the reducing is from the open end of the shell toward the base and after the upper margin of the shell has been reduced the tool 20 engages its upper reduced end and bears on the same during the remainder of the reducing or compressing operation, thus thickening the walls of the shell and preventing

elongation thereof. The shell 19 with the stem 15 attached is then placed in a die 21 similar to the die 14 and the compressing operation repeated by tools 22 and 23 similar to the tools 17 and 20, thus firmly clamping the base of the shell onto the flange 16 of the stem. The stem is formed with a passage 24 opening into the cup 25 and with an outlet passage 26. The stem is also elongated and threaded at its lower end for receiving a nut.

The lubricating device here shown is known commercially as a spring bolt used for connecting the leaf spring to the shackle 15 or bearing on a side sill of a motor vehicle, or to another leaf spring.

What I claim is:—

1. The process of forming a lubricating device including a cup, and a hollow stem 20 depending from the cup, the process consisting in the following steps:—(1) forming a central opening in the bottom of a cup shaped shell, (2) passing the stem which has a flange at its end, through the opening until the flange rests on the bottom of the shell, and (3) compressing the portion of the shell above the flange to clamp the flange on the bottom of the cup, substantially as and for the purpose described.

2. The process of forming a lubricating device including a cup, and a hollow stem depending from the cup, the process consisting in the following steps: (1) forming a central opening in the bottom of a cup 35 shaped shell of substantially the length of the finished cup, (2) passing the stem which has a flange at its end, through the opening until the flange rests on the bottom of the shell, and (3) compressing the portion of 40 the shell above the flange to clamp the flange on the bottom of the cup, by placing the cup with the stem therein in a die which surrounds the lower portion of the cup, and forcing a reducing die of less diameter than 45 the shell over the upper portion of the shell, substantially as and for the purpose specified.

3. The process of forming a lubricating device including a cup, and a hollow stem depending from the cup, the process consisting in the following steps: (1) forming a central opening in the bottom of a cup shaped shell of substantially the length of the finished cup, (2) passing the stem, which has a flange at its end, through the opening 55 until the flange rests on the bottom of the shell, and (3) compressing the portion of the shell above the flange to clamp the flange on the bottom of the cup by placing the cup with the stem therein in a die which surrounds the lower portion of the cup, and forcing a reducing die of less diameter than 60 the shell over the upper portion of the shell toward the closed end thereof, substantially as and for 65 the purpose set forth.

4. The process of forming a lubricating device including a cup, and a hollow stem depending from the cup, the process consisting in the following steps: (1) forming a central opening in the bottom of a cup 70 shaped shell of substantially the length of the finished cup, (2) passing the stem, which has a flange at its end, through the opening until the flange rests on the bottom of the shell, and (3) compressing the portion of 75 the shell above the flange to clamp the flange on the bottom of the cup, by placing the cup with the stem therein in a die which surrounds the lower portion of the cup, and forcing a reducing die of less diameter than 80 the shell over the upper portion of the shell, in a direction lengthwise of the shell from the open end of the shell toward the closed end thereof, and holding the shell at its end by a tool bearing on the edge of the shell, substantially as and for the purpose described.

5. The process of forming a lubricating device including a cup, and a hollow stem 90 depending from the cup, the process consisting in the following steps:—(1) reducing the diameter of the closed end of the cup shaped shell by forcing the shell into a reducing die and thereby thickening the reduced portion of the shell, (2) punching a 95 hole in the closed end of the shell, (3) passing the stem, which has a flange at its upper end, through the hole until the flange engages the bottom of the shell, and (4) compressing the portion of the shell above the 100 reduced portion into a circle of less diameter than said reduced portion, substantially as and for the purpose specified.

6. The process of forming a lubricating device including a cup, and a hollow stem 105 depending from the cup, the process consisting in the following steps: (1) reducing the diameter of the closed end of the cup shaped shell of substantially the length of the finished cup by forcing the shell into a reducing die by a tool bearing on the inner face of the closed end, and on the open end of the shell and thereby thickening the reduced portion of the shell, (2) punching a hole in 110 the closed end of the shell, (3) passing the stem having a flange at its upper end, through the hole until the flange engages the bottom of the shell and (4) compressing the portion of the shell above the reduced portion into a circle of less diameter than said 115 reduced portion, substantially as and for the purpose set forth.

7. The process of forming a lubricating device including a cup, and a hollow stem 125 depending from the cup, the process consisting in the following steps: (1) reducing the diameter of the closed end of a cup shaped shell of substantially the length of the finished cup by forcing the shell into a reducing die by a tool bearing on the inner 130

face of the closed end, and on the open end of the shell, (2) punching a hole in the closed end of the shell, (3) passing the stem which has a flange at its upper end, 5 through the hole until the flange engages the bottom of the shell, (4) compressing the portion of the shell above the reduced portion into a circle of less diameter than said reduced portion by placing the shell with the 10 stem therein in a die fitting said reduced portion and forcing a reducing die over the portion of the shell located out of the forming die, the reducing die moving lengthwise of the shell from the open end of the shell toward the closed end thereof and (5) holding 15 the shell from elongation by a tool on the open end of the shell, substantially as and for the purpose described.

8. The process of forming a lubricating 20 device including a cup, and a hollow stem depending from the cup, the process consisting in the following steps: (1) forming the base portion of a cup shaped shell adjoining the closed end thereof hexagonal by drawing 25 and pushing the shell into a die having a reduced portion at its inner end (2) punching a hole in the closed end of the shell, (3) passing the stem, with an hexagonal flange at its end, through the opening until the 30 flange fits within the hexagonal base of the shell and (4) compressing the portion of the shell above the hexagonal base into a circle of less diameter than the base, substantially as and for the purpose specified.

9. The process of forming a lubricating 35 device including a cup, and a hollow stem depending from the cup, the process consisting in the followings steps: (1) forming hexagonal, the base portion adjoining the closed end of a cup shaped shell substantially 40 the length of the finished cup by drawing and pushing the shell into a die having a reduced portion at its inner end, (2) punching a hole in the closed end of the shell, (3) passing the stem, with an hexagonal flange 45 at its end, through the opening until the flange fits within the hexagonal base of the shell, (4) compressing the portion of the shell above the hexagonal base into a circle of less diameter than the base by placing 50 the cup with the stem therein into a die inclosing the base portion of the shell, and forcing a reducing die over the portion of the shell above the base, the reducing die moving from the open end of the shell toward the base thereof and (5) holding the shell from elongating during the compressing operation, substantially as and for the purpose set forth.

In testimony whereof I have hereunto 60 signed my name in the presence of two attesting witnesses, at Syracuse, in the county of Onondaga, in the State of New York, this 30th day of June, 1913.

GEORGE W. BOWEN.
